UNITED STATES PATENT OFFICE

153,925

DESIGN FOR A FLIGHT TRAINER HOOD

Richard C. Dehmel, Summit, N. J.

Application September 14, 1946, Serial No. 133,327

Term of patent 3½ years

(Cl. D71—1)

To all whom it may concern:

Be it known that I, Richard C. Dehmel, a citizen of the United States of America and residing at 160 Summit Avenue, in the city of Summit, county of Union, and State of New Jersey, have invented a new, original, and ornamental Design for a Flight Trainer Hood, of which the following is a specification, reference being had to the accompanying drawings, forming a part thereof.

In the drawings:

Fig. 1 is a front perspective view of a flight trainer hood showing my new design;

Fig. 2 is a rear view in elevation of the design shown in Fig. 1, and

Fig. 3 is a side view in elevation of the aforesaid design.

The characteristic features of my design reside in the portions shown by means of full lines in the drawing.

I claim:

The ornamental design for a flight trainer hood, substantially as shown and described.

RICHARD C. DEHMEL.
